(57) CLAIM

The ornamental design for a template, as shown and described.

DESCRIPTION

FIG. 1 is a perspective view of the claimed design;

FIG. 2 is a top view of the claimed design;

FIG. 3 is a rear elevation view of the claimed design;

FIG. 4 is a front elevation view of the claimed design;

FIG. 5 is a left side elevation view of the claimed design; and,
